UNITED STATES PATENT OFFICE.

RUDOLF KIENINGER, OF CHICAGO, ILLINOIS.

DESIGN FOR A CANTEEN BOX.

Application filed December 27, 1926. Serial No. 20,158. Term of patent 3½ years.

To all whom it may concern:

Be it known that I, RUDOLF KIENINGER, a citizen of the United States, residing at Chicago, in the county of Cook and State of Illinois, have invented a new, original, and ornamental Design for Canteen Boxes, of which the following is a specification, reference being had to the accompanying drawing forming a part thereof, in which—

I claim:

The ornamental design for a canteen box, as shown.

In witness whereof I affix my signature.

RUDOLF KIENINGER.
